DESIGN FOR A HAIR CURLER

William H. Maxwell, Los Angeles, Calif.

Application August 12, 1943, Serial No. 110,899

Term of patent 14 years

(CL. D86—10)

To all whom it may concern:

Be it known that I, William H. Maxwell, a citizen of the United States, residing in the city of Los Angeles, county of Los Angeles, and State of California, have invented a new, original, and ornamental Design for a Hair Curler, of which the following is a specification, reference being had to the accompanying drawing, forming a part thereof.

The figure is a perspective view of a hair curler showing my new design.

I claim:

The ornamental design for a hair curler, as shown.

WILLIAM H. MAXWELL.
